UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

PRESSER MECHANISMS FOR SEWING-MACHINES.

1,350,301.

Specification of Letters Patent. Patented Aug. 24, 1920.

Application filed December 26, 1917. Serial No. 208,724.

To all whom it may concern:

Be it known that I, ALBERT H. DE VOE, a citizen of the United States, residing at Westfield, in the county of Union and State 5 of New Jersey, have invented certain new and useful Improvements in Presser Mechanisms for Sewing-Machines, of which the following is a specification, reference being had therein to the accompanying drawings.

10 This invention relates to sewing machines and particularly to the presser mechanisms thereof which coöperate with the feed-dogs in advancing the work.

In the presser mechanism of sewing machines as heretofore constructed the presser-bar carrying the presser-foot has been vibrated up and down with the feed-dog during each stitch-forming cycle of operations. Because of the weight of the presser-bar and 20 its consequent inertia a stronger spring is necessary to make the presser-foot and bar follow the feed-dog up and down than would be necessary if the presser-foot only vibrated up and down with the feed-dog and the 25 presser-bar remained substantially stationary. Especially is this true in high speed machines. Various attempts have been made to diminish the load imposed upon the feed-dog by reason of the weight and inertia of 30 the relatively heavy presser-bar but so far as is known no one of these attempts has been successful in eliminating the vibration of the presser-bar during each stitch-forming cycle of operations for all thicknesses of 35 work and for all speeds of machines.

In this invention it has been sought to eliminate vibration of the presser-bar during each stitch-forming cycle of operations in order to lessen the load on the feed-dog during 40 its work-advancing movements thereby bettering the speed of the machine and diminishing its noise in operation.

In this invention the presser-foot is yieldingly urged down upon the work to coöperate with the feed-dog on the opposite side thereof and the presser-bar yieldingly supported from the presser-foot, the two yielding means being so proportioned and arranged that during the normal operation of 45 the machine the foot vibrates up and down

but the presser-bar remains substantially stationary. When the work varies in thickness the presser-bar shifts gradually to adapt itself to the different thickness of the work passing under the presser-foot and 55 by the time several stitches have been made, it arrives at its new position in which it remains stationary while the foot alone continues to vibrate up and down in a certain desirable vibrating relation with the presser-bar.

The invention is illustrated in the accompanying drawings in which Figure 1 shows a machine in front elevation, part of the head being broken away. Fig. 2 shows a 65 machine in end elevation with the face-plate of the head removed to expose the mechanism. Figs. 3 and 4 show longitudinal and transverse vertical sections respectively through the foot illustrated in Figs. 1 and 2. Fig. 5 shows a detail in vertical section through the presser-bar in the form illustrated in Figs. 1 and 2. Fig. 6 shows a modified form of the invention in end elevation and in Fig. 7 the same is shown in front 70 elevation.

In the accompanying drawings one form of the invention is illustrated in Figs. 1 to 5, inclusive. Overhanging the work-support 1 in which is inlaid the usual throat-plate 2 80 is an arm 3 sustaining in suitable bearings a rock-shaft 4 having at its end within the head 5 a crank-arm 6 connected by a link (not shown) to a needle-bar 8 slidably mounted in the head.

The under thread-handling mechanism may be of any suitable form as the invention is capable of use with almost any of the known stitching mechanisms.

In the head 5 in rear of the needle-bar a 90 presser-bar is supported in suitable bearings. The presser-bar, Fig. 5, comprises a relatively thin tube or hollow cylinder 10 internally of which bearings 11 are formed or secured in any suitable manner. In each of 95 these bearings 11 apertures are formed in line with each other to slidably receive a pin 13 adapted for endwise movement therein independently of the presser-bar. A block 14, Fig. 2, is externally secured to the 100

presser-bar intermediate its ends within a U-shaped recess 15 in a sliding sleeve 16 loosely embracing the presser-bar. A friction-roller 17 carried by the sliding sleeve 16 and extending laterally therefrom is arranged in the path of a lifting lever 18 pivoted at 19 to a fixed part of the frame with a cam-face 20 for elevating the presser-bar through the sliding sleeve and block in a manner well known.

From the lower end of the presser-bar an arm 21 extends rearwardly in the direction of feed. The arm is channeled longitudinally or grooved as indicated at 22 to receive a rib 23 pivoted at 24 to the arm and forming part of the shank or body portion 25 of a presser-foot to which a work-engaging member or pad 26 is pivoted at 27. The arm 21 is also channeled vertically as indicated at 28, Fig. 2, to receive and clear an angle or finger 29 secured by screw 30 to the rib of the shank portion of the foot with the bent upper end 31 of the finger extending across the arm 21 carried by the presser-bar. To the arm 21 fast on the lower end of the presser-bar a pin 32 is fixed in a substantially upright position with its adjustable head 33 spaced from the bent end 31 of the finger through which the shank of the pin 32 passes loosely. Between the two abutments thus formed by the head 33 of the pin and the bent end 31 of the finger a resilient yielding element in the form of a coiled spring 34 is interposed. This coiled spring 34 yieldingly sustains or supports the weight of the presser-bar and its adjuncts from the presser-foot and by adjusting the head 33 the tension of the spring may be made a little greater than the weight of the bar and its adjuncts so as to make the presser-bar and its adjuncts respond quickly to a difference in thickness of the work being operated upon.

For yieldingly holding the presser-foot down upon the work a spring 35 is arranged upon the top of the overhanging arm with one of its ends 36 resting upon the top of the pin 13 and with its other end 37 resting on the top of the overhanging arm. A bracket 38 overhangs the spring 35 and carries an adjusting screw 39 for varying its tension. The lower end of the pin 13 rests upon the top of the rib 23 of the shank portion of the presser-foot.

Coöperating with the presser-foot is the usual feed-dog 40 to which up and down and work-advancing movements are imparted in a well known manner.

The machine represented in the drawing is of the chain-stitch type and the thread-controlling mechanism illustrated handles the needle-thread of this type of machine. It comprises differentially movable arms 41 and 42 operatively arranged on opposite sides of a wire or bar 43, one of the arms

being fast to the needle-bar and the other being fast to the driving link connecting the needle-bar and the crank-arm. These differentially moving arms and bar 41, 42 and 43 control the needle-thread in a manner already disclosed in the prior art as may be ascertained from my prior Patent No. 1,167,634, granted January 11, 1916.

The thread-controlling mechanism also includes a means for varying the take-up action as the thickness of the work changes. It includes an arm 44 apertured at its free end 45 and fixedly secured to a rock-shaft 46 whose axis is parallel to the line of feed. This rock-shaft 46 within the head 5 of the machine is provided with an arm 47 carrying a friction-roll 48 extending between the jaws 49 and 50 fixedly secured to the presser-bar in any suitable manner being steadied or guided as shown by the depending pin 51. When the presser-bar is shifted upwardly the free end 45 of the arm 44 moves downwardly and thereby increases the pulling off action of the take up during its rise to its highest position which it will be observed is due to the fact that the free end 45 of the arm is below the upper limit of the path in which the take-up arms 41 and 42 move as those skilled in the art will readily understand.

In the operation of the machine, and supposing a thin piece of material to be under the presser-foot, when the feed-dog rises from beneath the throat-plate and engages the work against the downward thrust of the presser-foot, the latter is vibrated about its pivotal connection 24 with the presser-bar. If the work passing under the presser-foot does not change in thickness the vibrations imparted to the presser-foot through the action of the feed-dog are not transmitted to the presser-bar because the spring 34 interposed between the presser-foot and the presser-bar acts as a shock-absorber or cushion. This action of the spring is believed to result from the inertia of the presser-bar and its fixedly connected parts, also from the location of the bent end 31 of the finger relative to the pivotal connection 24 and also from its own inertia or lag. When the work increases in thickness the repeated blows upwardly against the under surface of the presser-foot put the spring 34 under greater compression and after a few stitches have been made, the presser-bar gradually assumes a new position substantially the same distance above the upper surface of the work, the presser-foot continuing to vibrate. And when the work decreases in thickness the presser-bar is lowered correspondingly.

The invention comprehends broadly a presser-foot which is free to vibrate under the action of a main spring in combination with a member or element shiftable in the

frame or head of a sewing machine to which member the presser-foot is movably connected, the member being sustained or floated a definite and substantially constant distance above the upper surface of the work so as to maintain a desirable and constant relation between the vibrating presser-foot and the member however the thickness of the work may vary.

10 In Figs. 6 and 7 the invention is illustrated in another form and its differences from the already described form are clearly depicted in the drawings. In the form of the invention illustrated in Figs. 6 and 7 the 15 presser-foot comprises a work-engaging portion 60 pivoted at 61 to a body portion 62 from which rises a stud 63 apertured axially to receive a pin 64 substantially like the pin 13 of the previously described form 20 of the invention. A spring 65, similar to the spring 35 acts upon the upper end of the pin 64 and holds the presser-foot yieldingly down upon the work in the same manner as has been described.

25 The presser-bar in this form of the invention is like the presser-bar of the previously described form of the invention. Instead, however, of sustaining the weight of the presser-bar from the presser-foot 30 through a rearwardly extending arm fixed to the presser-bar, the weight of the same is sustained by a light coiled spring 66 interposed between the top of the pin 63 which slides within the hollow cylinder 67 of the 35 presser-bar and a bearing 68 arranged centrally of the cylindrical shell 67.

40 Preferably the upper end of the pin 64 is provided with an anti-friction device in the form of a ball bearing 69 suitably secured within the enlarged and shouldered head 70 steadyng the upper end of the pin 64. The lower end of the pin is secured within the shank portion of the foot by the 45 set-screw 71.

45 To prevent the presser-foot from turning about the axis of the presser-bar a bushing 72 is fixedly secured within the frame of the machine and its slotted lower end 73 embraces the parallel walls 74 of the shank 50 portion of the foot, the shank 62, however, being free to slide up and down within the slot 73.

55 The modification shown in Figs. 6 and 7 operates broadly in substantially the same way as the other illustrated embodiment of the invention, the main spring 65 holding the presser-foot upon the work to coöperate with the feed-dog in advancing the same and the spring 66 sustaining the weight of 60 the presser-bar from the presser-foot.

In both forms of the invention it is to be noted that the feed-dog is not only relieved of the work of vibrating the presser-bar but is also relieved of the work of vibrating the controller-arm 44 which forms part of the

thread-controlling mechanism. As the controller-arm 44 is a desirable adjunct in certain types of machines, especially chain-stitch machines, it is obviously advantageous to relieve the feed-dog of the work of 70 vibrating such a member uselessly during each stitch-forming cycle of operations.

In both forms of the invention the presser-foot may be lifted to introduce or remove the work by raising the lever 18. In 75 the form of the invention shown in Figs. 1-5, inclusive, the presser-foot is lifted with the presser-bar by engagement of the arm 21 with the finger 31 overlying it. In the form of the invention illustrating Figs. 6-7 80 the presser-foot is lifted with the bar by reason of the engagement of the upper end of the cylindrical shell 67 with the shouldered head 70 of the pin 64 which it will be remembered is fastened at its lower end to 85 the presser-foot by the set-screw 71.

Having thus set forth the nature of the invention, what I claim herein is:—

1. In a sewing machine, a presser mechanism including a foot and a presser-bar, a 90 spring yieldingly urging said foot into engagement with the work, a second spring supported by said foot and sustaining said presser-bar, in combination with work-feeding mechanism including a feed-dog movable up and down whereby during the normal operation of the machine the presser-bar is prevented from vibrating up and down with the feed-dog during the stitching of work of a uniform thickness what- 95 ever it may be. 100

2. In a sewing machine, in combination, a presser mechanism including a presser-bar and a presser-foot movably connected to said presser-bar, a feeding mechanism including a feed-dog, resilient means solely acting to hold the presser-foot down upon the work to coöperate with the feed-dog in advancing the same, and independently acting resilient means for supporting said presser-bar from said foot whereby during the normal operation of the machine in stitching a portion of the work of uniform thickness whatever it may be the presser-bar is sustained stationary. 110 115

3. In a sewing machine, a presser mechanism including a foot and a presser-bar movably connected to said foot, work-feeding mechanism including a feed-dog, a spring, stationary means against which one 120 end of the spring reacts as an abutment, means operatively connecting the other and free end of the spring and said foot to yieldingly urge the presser-foot down upon the work, and yielding means interposed between the presser-foot and the presser-bar for yieldingly sustaining said presser-bar. 125

4. In a sewing machine, in combination, a presser-mechanism including a presser-foot having a shank portion and a work- 130

- engaging portion pivotally connected together, a presser-bar, an arm fixed to said presser-bar and arranged transversely thereof, a pivotal connection between said 5 arm and the shank portion of the foot and located out of line with the axis of the presser-bar, an abutment fixedly connected to the presser-bar, a coöperating abutment fixed to the presser-foot, a spring interposed between said abutments for yieldingly sustaining the presser-bar from the presser-foot, and elastic means yieldingly holding the presser-foot down upon the work and having no action on the presser-bar in combination with work-feeding mechanism having a rising-and-falling feed-dog.
5. In a sewing machine, a presser mechanism including a presser-foot having relatively movable portions operatively connected together, a presser-bar, an arm extending rearwardly from the lower end of said presser-bar, a pivotal connection between said arm and presser-foot located at the free end of the arm, means for yieldingly sustaining 10 said presser-bar from said presser-foot, and spring means arranged to operatively urge the presser-foot down upon the work independently of the presser-bar in combination with work-feeding mechanism including a 15 rising-and-falling feed-dog.
6. In a sewing machine, a presser mechanism including a presser-foot having relatively movable portions operatively connected together, a presser-bar, an arm extending 20 rearwardly from the lower end of said presser-bar, a pivotal connection between said arm and one portion of said presser-foot, means for yieldingly sustaining said presser-bar from said presser-foot, a spring, a pin 25 arranged within said presser-bar and extending in the direction of its length, said pin having its opposite ends in contact with a portion of the presser-foot and the spring, in combination with work-feeding mechanism including a feed-dog.
7. In a sewing machine having a frame and a throat-plate, a presser mechanism including a member movably connected to the frame to permit of varying the position of 30 the member relative to the throat-plate when work of different thickness is being sewed, a presser-foot, connections between the presser-foot and member permitting of variations of the foot relative to the member during 35 normal cycles of stitch-forming operations, in combination with work-feeding mechanism including a feed-dog movable up and down through the throat-plate into and out of contact with the work, a spring coöperating with said feed-dog to enable it to grip the work against the presser-foot, and a second spring supporting said member elastically from said presser-foot for gradually shifting the position of said member when

the work passing under the presser-foot varies in thickness whereby the relation of the presser-foot and member may be maintained substantially the same for different thicknesses of work and said member prevented from vibrating up and down with the 70 feed-dog.

8. In a presser mechanism for sewing machines, a work-engaging foot, a shiftable member, connections between the foot and the shiftable member permitting of vibrating the foot while the member is stationary, means holding the foot in parallel relation to the line of seam-formation, a plurality of springs acting upon said foot to thrust the foot down upon the work and to sustain the 80 shiftable member from the foot, said springs and connections being arranged to relieve the shiftable member of the vibrations to which the presser-foot is subjected during a succession of stitch-forming operations when 85 sewing material of uniform thickness whatever the thickness may be, in combination with a feeding mechanism including a feed-dog.

9. In a presser mechanism for sewing machines, in combination, a presser-foot, a presser-bar freely shiftable toward or away from said presser-foot at any time, means for holding the presser-foot down upon the work acting independently of the presser-bar, and means controlled by the thickness of the work being operated upon for shifting the presser-bar independently of said first-mentioned means to maintain the presser-bar a substantially constant distance 100 above the upper surface of the material being operated upon whatever may be its thickness.

10. In a sewing machine, a presser mechanism including in combination, a presser-foot, a member freely shiftable in opposite directions and relative to the presser-foot throughout each of successive stitch-forming cycles of operations, said member being operatively connected to the presser-foot, a stationary abutment, a spring reacting against said stationary abutment and operating to hold the presser-foot down upon the work, and a second spring reacting against the presser-foot and effective upon said member to sustain it substantially stationary while the presser-foot is vibrating during a plurality of stitch-forming operations.

11. In a sewing machine having a frame, 120 a presser mechanism including a presser-foot and a member connected to the presser-foot which is shiftably mounted in a fixed part of the frame of the machine, means for yieldingly holding the presser-foot 125 down upon the work, and means for yieldingly supporting the weight of said member from the presser-foot, in combination with

thread controlling mechanism including a movable thread engaging member operatively connected to the first mentioned member, whereby the movable member of the 5 thread-controlling mechanism may be prevented from vibrating during a succession of stitch-forming operations.

12. In a sewing machine having a frame, a work-feeding mechanism including a feed-dog movable into and out of engagement with the work at the beginning and ending of a feeding operation, a presser-foot, a member shiftably mounted in said frame and operatively connected to said foot, 10 means governing the coöperative action of the presser-foot with the feed-dog without acting upon said member, and means for gradually shifting said member toward and from the plane in which the work travels 15 and when the work varies in thickness, said last-named means being arranged to prevent up and down vibration of said member during normal feeding operations of the machine when the presser-foot is being vibrated by the feed-dog.

13. In a sewing machine having a frame, work-advancing mechanism including a feed-dog movable into and out of engagement with the work at the beginning and 20 ending of a feeding stroke, a presser-foot, a member shiftably mounted in said frame and operatively connected to said foot, a spring governing the coöperative action of the presser-foot with the feed-dog when the 25 work is being advanced step-by-step, and automatic means governed by the thickness of the work for shifting said member as the work varies in thickness without subjecting the member to the vibrations to 30 which the presser-foot is subjected during advance of work having a uniform thickness.

14. In a sewing machine having a frame, in combination, work feeding mechanism including a feed-dog, a presser-foot, a member to which the presser-foot is operatively connected, means urging said presser-foot down upon the work and permitting it to vibrate with the feed-dog without vibrating said 45 member to which it is operatively connected, said member being shiftable relative to the frame of the machine, and a thread-controlling mechanism including an arm whose position is governed by the shiftable member to vary the action of the thread-controlling means when the work varies in 50 thickness, whereby vibrations of the presser-foot in its coöperative action with the feed-dog may be prevented from reaching the 55 arm of the thread-controlling mechanism during the normal operation of the machine upon any uniform thickness of work.

15. In a sewing machine having a frame, in combination, work-feeding mechanism including a feed-dog, a presser-foot, a mem-

ber to which the presser-foot is operatively connected, means urging said presser-foot down upon the work permitting it to vibrate with the feed-dog without vibrating said member to which it is operatively connected, said member being shiftable, an element of the sewing machine whose position is varied with the thickness of the work to vary the operative action of the machine which element is operatively connected to 70 said member, whereby vibrations of the presser-foot in its coöperative action with the feed-dog may be prevented from effecting the element during the normal operation of the machine upon any uniform thickness of the work.

16. In a sewing machine having a work-support and stitch-forming mechanism including a needle, in combination, feeding mechanism including a feed-dog and presser mechanism including a presser-foot coöperating with said feed-dog, means confining said presser-foot to translatory movement in a direction perpendicular to the plane of the work-support, a spring for urging said presser-foot down upon the work, a relatively fixed abutment against which said spring reacts, and a pin interposed between the presser-foot and the spring and acting independently of said confining means for 85 transmitting the force of the latter to the former.

17. In a sewing machine having an overhanging arm, in combination, feeding mechanism including a feed-dog, presser mechanism including a presser-foot coöperating with said feed-dog, means confining said presser-foot to translatory movement in a direction perpendicular to the plane in which the work moves, a spring sustained by the overhanging arm for urging the presser-foot toward the feed-dog, a pin interposed between the presser-foot and the spring for transmitting the force of the latter to the former, a sleeve embracing said pin, a bushing on said sleeve bracing said pin intermediate its ends, a relatively light spring supporting said sleeve from the presser-foot, and a thread controlling mechanism including a thread engaging arm connected to 100 said sleeve, said arm and sleeve being floated on said relatively light spring whereby they are shifted by variation in the thickness of work passing under the presser-foot without being subjected to the vibrations which 105 the feed-dog communicates to the presser-foot during each of successive stitch-forming cycles of operation.

18. In a sewing machine, in combination, a presser mechanism including a presser-bar and a presser-foot movably connected to said presser-bar, feeding mechanism, yielding means acting independently of the presser-bar to hold the presser-foot against 115 the work to coöperate with the feeding 120

mechanism, and independently acting yielding means for connecting the presser-bar and foot whereby during normal operation of the machine in stitching the presser-bar may remain stationary.

19. In a sewing machine, in combination, a presser mechanism including a presser-bar and a presser-foot, yielding means for

holding the presser-foot against the work and acting independently of the presser-bar, ¹⁰ and yielding means connecting the presser-bar and presser-foot.

In testimony whereof I have signed my name to this specification.

ALBERT H. DE VOE.
